2 SHEETS—SHEET 2.

UNITED STATES PATENT OFFICE.

JOHN H. SCHOTT, OF BOULDER, COLORADO, ASSIGNOR OF ONE-FIFTH TO JAMES G. ARCHIBALD, ONE-FIFTH TO J. EMMONS DE KALB, AND ONE-FIFTH TO MICHAEL M. RINN, ALL OF BOULDER, COLORADO.

PULLING-MACHINE.

1,327,492.

Specification of Letters Patent.

Patented Jan. 6, 1920.

Application filed May 29, 1919. Serial No. 300,602.

To all whom it may concern:

Be it known that I, JOHN H. SCHOTT, a citizen of the United States, residing at Boulder, in the county of Boulder and State 5 of Colorado, have invented certain new and useful Improvements in Pulling-Machines; and I do declare the following to be a full, clear, and exact description of the invention, such as will enable others skilled in the 10 art to which it appertains to make and use the same.

This invention relates to improvements in pulling machines, particularly to that type adapted for use in wire stretching, and has 15 for its primary object the provision of a compact, simply constructed device, one requiring a minimum amount of power to operate, yet being highly efficient in performing its functions.

Another object is to provide a device of 20 this character including a novel means for positively engaging the wire gripping elements with the wire being stretched, thereby preventing accidental slipping or disengagement from the machine, of the wires.

With these and numerous other objects in view my invention resides in the novel features of construction and arrangement of parts as will be set forth in the specification 30 and claims and clearly illustrated in the accompanying drawings which form a part of this application and in which,

Figures 1 and 2 are side elevations of the device in use, showing the movable wire 35 grippers in different positions;

Fig. 3 is a top plan view of Fig. 1;

Fig. 4 is a horizontal sectional view taken on the line 4—4 of Fig. 1;

Fig. 5 is a vertical longitudinal sectional 40 view taken on the line 5—5 of Fig. 4.

Fig. 6 is a vertical transverse sectional view taken on the line 6—6 of Fig. 4 and;

Fig. 7 is a detail vertical sectional view of 45 one of the grippers and slides taken on the line 7—7 of Fig. 6.

In these drawings which constitute a part of the application and in which similar reference characters designate corresponding parts throughout the several views, the number 50 1 indicates broadly a substantially rectangular casing which is divided into two compartments by a vertical longitudinally extending partition 2, said partition

being provided with three parallel transverse openings or apertures for a purpose to 55 be hereinafter set forth, said casing having one side closed by a removable plate 3, and its other side partially closed by narrow strips 4 secured to the upper and lower edges.

Covering the remaining open space between the strips 4, is a back plate 5 which is 60 removably secured to the end portions of the casing, said plate being provided with a pair of parallel laterally projecting flanges 6, preferably though not necessarily, formed integral with the plate, these flanges and the back plate forming a guide 10 adapted to receive a pair of movable slides or pullers 7. The back plate 5 is provided near each end 70 with a longitudinally extending slot 8 opening into the casing. The upper flange is provided with longitudinal slots 9 at points near each end, said slots being adapted to guide the movable pins or screws which are 75 secured in the upper edges of the slides or pullers at points approximately midway their lengths.

Extending laterally from the lower end of the slide or pullers 7 and preferably 80 though not necessarily formed integral therewith, are fixed jaw members 11, provided with gripping teeth on their upper faces, said teeth being adapted to coact with the teeth on the lower edges of yieldable 85 jaw members 12 which are mounted on outwardly projecting lugs or studs 13 formed on the slides 7, said jaws forming grippers to hold the wire being stretched. Vertically aligned with the slots in the upper flange 6 and of similar dimensions are slots 14 in the lower flange adapted to guide the 90 movable pins or screws which are secured in the lower smooth face of the fixed jaws 11, said pins or screws in the lower and upper flanges being adapted to retain the slides or pullers in proper relative position with the 95 guide 10.

The movement of the yieldable jaws 12 is controlled by coil springs 15 disposed 100 around the studs 13, one end of each spring being secured to the stud and the other end extending through a slot in the jaw and then bent at right angles, the tension of the spring forcing the teeth against the fixed 105 jaw member.

Projecting laterally inward and guided in the slots 8 in the back plate of the guide 10 are studs 16 which are preferably though not necessarily formed integral with the slides or pullers 7.

Mounted in the parallel openings in the partition 2 of the casing, are three shafts, the endmost shafts 17, at their ends adjacent the back plate of the guide 10, loosely carrying the gear wheels 18 which are provided with crank pins 19 adapted to be connected to the stud 16 of the slides or pullers by a link 20.

Keyed to the central shaft 21, at the end 15 adjacent the loosely mounted gear wheels 18 is a small gear 22 whose teeth mesh with those of the other gears 18. A gear wheel 23 of approximately the same dimensions as the large gears 18, is keyed to the central 20 shaft on the opposite side of the partition. A small gear wheel 24 is keyed to one of the endmost shafts, its teeth meshing with those of the large gear 23.

The shafts extend through openings in 25 the cover plate 3, said openings forming bearings for the shafts. The endmost shaft which carries the small gear 24 is slightly longer than the remaining two, for the purpose of receiving an operating crank 25 keyed thereto.

For a purpose to be fully described, a pair 35 of longitudinally adjustable stops 26 are mounted on the upper flange of the guide 10, said stops being illustrated in the drawings as small blocks 27 disposed on the under side of said flange, having upstanding threaded studs projecting through longitudinally extending slots in said flange and receiving nuts thereon. These stops may be 40 in the form of leaf springs disposed in slots in the flange and extending a short distance below said flange.

In operation, the machine is first hitched to a post, by means of a suitable chain, one 45 end of which is secured to an eye 28 on one end of the casing 1. The wire to be stretched, is then placed between the fixed and yieldable or movable jaws on the slides or pullers, separation of said jaws being 50 made possible by the handles 29 which are suitably secured to the movable jaws and extend vertically upward. The handles are released upon placing the wire between said jaws and the next step is merely to turn the 55 crank.

As will be readily seen, turning the crank operates the gears and simultaneously moves the slides or pullers 7 in opposite directions. When the slides are at their innermost positions and about to move outwardly, the 60 jaws near the end of the casing adjacent the post, grip the wire and tighten it, while the other jaws are sliding over said wire, in the opposite direction, for the purpose of 65 getting a new grip on it. In order to assure

a firm hold on the wire the aforementioned stops 26 are positioned in the path of travel of the grippers striking lugs 30 on the movable jaws, so that just prior to the beginning of the working strokes the yieldable jaws 70 are forced against the wire, getting a firm grip thereon.

In the drawings, certain specific details of construction have been shown for accomplishing probably the best results, and in the 75 preceding, such details have been described, but it is obvious that I need not be restricted thereto otherwise than to the extent claimed.

I claim—

1. A machine of the class described comprising a box-like casing, a guide on said casing having slots, a pair of slides carried by said guide, a pair of yieldable gripping devices on said slides, a pair of studs on said slides movable in said slots of said 80 guide, a partition in said casing, parallel shafts mounted in said partition, gear wheels mounted on certain of said shafts on the side of the partition adjacent the guide, crank pins on said wheels, links connecting 85 said crank pins and studs and means on the opposite side of the partition for rotating said gear wheels whereby the slides will be simultaneously moved in opposite directions. 90

2. A machine of the class described comprising a box-like casing, a guide on said casing having slots, a pair of slides carried by said guide, a pair of yieldable gripping devices on said slides, a pair of studs on 100 said slides movable in said slots of said guide, a partition in said casing, parallel shafts mounted in said partition, a handle on one of the endmost shafts on one side of the partition, a pair of gear wheels 105 mounted on the central shaft and aforesaid endmost shaft, a pair of gear wheels on the endmost shafts on the opposite side of the partition, crank pins on said wheels, links connecting said crank pins and studs and an intermediate gear mounted on the 110 central shaft and adapted to transmit power to the last named gear wheels whereby the slides will be simultaneously moved in opposite directions. 115

3. A machine of the class described including a guide, a wire puller slideable in said guide, means for manually moving the puller, a yieldable wire gripper mounted on said puller, means for operating said puller 120 and means on said guide in the path of travel of said gripper for forcing the same into firm engagement with the wire being stretched.

4. A machine of the class described including a guide, a wire puller slideable in said guide, means for manually moving the puller, a yieldable wire gripper mounted on said puller, means for moving said puller and a stop on said guide in the path of 125 130

travel of the gripper for forcing the same into firm engagement with the wire being stretched.

5. A machine of the class described including a guide, a pair of slides in said guide, said slides being substantially L-shaped in cross section, gripping teeth on the upper faces of the horizontal flanges of said slides, a pair of substantially cam 10 shaped jaws pivotally mounted on the slides and having teeth for coöperation with the other teeth to grip a wire to be stretched, stops on said guide in the path of travel of the jaws and lugs on the jaws to engage 15 said stops at the beginning of each working stroke whereby the pressure of the jaws on the wire is increased to hold said wire.

6. A machine of the class described comprising a box-like casing, a guide on said 20 casing having slots, a pair of slides carried by said guide, a pair of yieldable gripping

devices on said slides, a pair of studs on said slides movable in the slots of said guide, gearing in the casing for simultaneously moving the slides in opposite directions, and 25 coacting parts on said guide and gripping devices to force the gripping devices into firm engagement with the wire at the end of each working stroke.

7. A machine of the class described including a guide, a pair of slides in said guide, means for simultaneously moving the slides in opposite directions, wire gripping cams mounted on said slides, spaced stops on said guide, and means on the cams for 35 engagement with said stops at the beginning of each working stroke to force the cams into firm engagement with the wire being stretched.

In testimony whereof I have hereunto set 40 my hand.

JOHN H. SCHOTT.
